FIRE ALARM SYSTEM

Roger W. Curtis, Bethesda, and Nathan Kaplan,
Silver Spring, Md.

Application July 3, 1956, Serial No. 595,806

10 Claims. (Cl. 340—227)

(Granted under Title 35, U. S. Code (1952), sec. 266)

The invention described herein may be manufactured and used by or for the United States Government for governmental purposes without payment to us of any royalty thereon.

The present invention relates to certain improvements in thermal flame detectors and to the method of making the same. More particularly, the present invention relates to a temperature responsive device which will selectively energize a fire alarm apparatus at a predetermined abnormal temperature condition surrounding the device.

In the prior art, it has been customary practice to utilize some system in which an outside power supply, usually a battery is required to energize the fire alarm, the thermal detector being operative only to energize some sensitive relay as in a thermocouple system, or to establish a circuit from the battery to the fire alarm. In the latter type, an electrode and fused salt combination is most commonly used wherein the salt will establish a conductive path for electricity at some predetermined increase in temperature, the salt being nonconductive at normal temperatures and up to the predetermined value. In both types of thermal detection, certain disadvantages attend their use, including a substantial time lag between the initial predetermined temperature condition and the energization of the alarm, a tendency to become insensitive after one or two operations, and the necessity of using an outside power source to energize the fire alarm. It is the purpose of the present invention to obviate the foregoing and other difficulties and disadvantages in the prior art by substituting a thermal detector which will not only signal the rise to a predetermined temperature level but, of itself, will develop the electrical output to actuate the alarm, the detector operating on the principle of a primary cell. In this way, by combining the detecting means with the energizing means, not only is an outside power supply eliminated but, in addition, a more direct and efficient system is made available. Accordingly, it is a primary object of this invention to provide a thermal detector which will accomplish the above mentioned advantages, is dependable in operation, and does not become impaired in sensitivity and accuracy for a reasonable number of operations.

It is another object to provide a system wherein the minimum operative temperature can be determined by the particular system ingredients selected.

Another object is to provide a system which will respond rapidly to the operative temperature to energize the fire alarm.

It is a further object to provide a thermal detector which is nonconductive up to the predetermined temperature level, and will return quickly to a nonconductive state upon a temperature reduction below the predetermined level.

A still further object is to provide a fire alarm system which is flexible, rugged, inexpensive to manufacture and install, and which comprises a minimum number of parts. Accordingly, the system is more readily conformable for

2

installation and detection in an increased number of selected locations and in practically any type configuration desired.

To accomplish the foregoing general objects, and other 5 more specific objects which will hereinafter appear, the present invention will be more fully understood by reference to the following detailed description and drawings in which:

Figure 1 is a schematic view of a line type detector in 10 the form of a continuous loop having an indicator electrically connected thereto.

Fig. 2 is a plan view, partly in section, of a line type detector in accordance with the invention.

Fig. 3 is a cross-sectional view of the invention taken 15 on the lines 3—3 of Fig. 1.

Fig. 4 is a right end view of the invention shown in 20 Fig. 2.

Fig. 5 is a schematic view of a continuous type detector in the form of a sheet, having an indicator electrical- 25 ly connected thereto.

Fig. 6 is a schematic view of a system having a hub and spoke arrangement, the indicator being the hub and the detector being the spokes.

Referring more particularly to the drawings, there is 30 shown in Fig. 1, a fire alarm system 10 having an elongated thermal electric cell or loop detector 11, and indicator 12 connected in electrical parallel relationship therewith. As shown in Figs. 2-4, the cell or detector 11 includes an outer tubular electrode 13 formed of a first metallic element, and an inner wire electrode 14 formed of a second dissimilar metallic element, the inner electrode being wrapped with an inorganic fibrous spacer material 15 which has been impregnated with a fused salt electrolyte, not separately shown.

35 As seen in Fig. 1, the detector 11 may be flattened as in Fig. 3, then bent or twisted as desired to fit the contour of any appropriate space or compartment 16 and extended through a firewall 17 for electrical connection to the indicator 12. The indicator 12 may then be connected to an alarm 21 by means of a lead 18 connected across the two ends of the outer electrode 13, and a lead 19 connected across the two ends of the inner electrode 14; the leads 20 are then connected to fire alarm 21 with leads 18 and 19 thereby establishing an electrical parallel relationship between the detector 11 and fire alarm 21.

40 In my preferred embodiment, the outer electrode 13 is in the form of a nickel tube, the inner electrode 14 being in the form of an elongated magnesium strip. The fibrous spacer 15, of material such as glass or asbestos tape, is 45 dipped into a bath of salt solution, such as an eutectic mixture of potassium and lithium chlorides with suitable depolarizers, for a sufficient time to allow the salt to impregnate the spacer and to solidify. The electrode 14 is then inserted into the spacer 15, the spacer and 50 inner electrode combination in turn, being interposed within the outer electrode 13. The spacer and inner electrode combination are snugly engaged with one another and should tightly fit within the outer electrode. Other aspects of importance in the construction of the 55 detector are, of course, that the inner and outer electrodes be formed of dissimilar metals, each of a substantially higher melting point than that of the electrolyte itself, and the composition of the electrolyte should be carefully regulated in proportions so that the initial melting 60 of the insulating material will occur at the predetermined temperature level. At this level, the electrical conductance of the electrolyte will rapidly increase to establish an electrical circuit between the electrodes and to initiate an 65 electromotive force or voltage across the ends of the dissimilar metallic electrodes to the fire alarm.

65 It is to be understood also that the spacer separating the electrodes, although preferably of the composition above 70

described, may be any of a large number of nonconductive materials having various shapes so long as the spacer prevents shorting of the electrodes and permits the electrolyte, when molten, to wet both electrodes; however, it has been found that my preferred embodiment is most effective in rapidly melting at the predetermined level to energize the indicator, and subsequently upon cooling of the fire detector to return to its normally solid condition forming a sheath or sleeve of high electrical resistance between the electrodes, and further capable of repeated operations in the event of additional temperature increases.

The simplicity and ease of making and installing the thermal detector and indicator make possible various configurations and adaptations of the device. As shown in Figures 2 and 4, the circular thermal detector may be bent and/or twisted into the desired shape, or may be flattened as in Figs. 1 and 3. In addition, the detector can be a loop as seen in Fig. 1 or can be straight with indicating means at only one end as seen in Fig. 2, or may have additional shapes with indicating means at either or both ends.

In assembling the thermal detector 11 in Fig. 2, it is important that the detector assembly be hermetically sealed or insulated at the ends thereof to protect it and to prevent shorting between the electrodes. Fig. 2 shows the detector 11 sealed at the end to which the indicator 12 is to be connected by means of a glass bead seal 21 having a conductive pin 23 extending therethrough, the pin 23 being electrically connected to the electrode 14. If desired, the other end can also be hermetically sealed as described above, or by any one of the well known sealing means, such as by crimping as at 23. In utilizing either the glass bead seal 22 or the crimped portion 23, the inner electrode 14 is foreshortened somewhat for placement of the seal within the outer electrode to prevent electrical shorting between the electrode ends. The alarm device 21, which is electrically connected to the conductive pin 23, or across the leads 20 may consist either of an electric lamp as shown in Fig. 1, or an electric bell or buzzer system, and as shown in Figs. 1 and 2, a complete rupture occurring at any point along the detector as a result of an abnormal increase in temperature nevertheless will not impair the operability of that portion of the detector which is still in current conducting relationship with the alarm.

Figs. 5 and 6 illustrate other possible configurations in combining the thermal detector and indicator: Fig. 5 shows an outer electrode plate 13a and inner electrode plate 14a, one or more indicators 12 being connected across the electrodes 13a and 14a at any point or points. In this form, the electrode 13a consists of a large bimetallic square strip of nickel or other related metal, and the electrode 14a consists of a smaller dissimilar bimetallic square, preferably of magnesium juxtaposed with and spaced from the electrode 13a by means of a fused salt impregnated nonconductive spacer, not shown, thereby forming a detector in the form of a continuous sheet. In Fig. 6, the indicator 12 acts as the hub of the fire alarm system, the detectors 11b being the spokes, radiating therefrom in all directions, in either a two-directional or a three-directional system. As shown, the detectors 11b are electrically connected in parallel, the indicator 12 being connected across the electrodes of the detector 11b.

Another important application of the invention is as an overheat alarm system for aircraft engine support members. This is not, strictly speaking, a fire alarm system. It is known that the strength of any supporting member, such as a beam, at any particular time, is a function of the temperature of the beam, the strength of the beam decreasing as the temperature increases. An excessively overheated beam could fail and no longer support the engine. The line detector of this invention can be affixed to the beam along its entire length, the portion of the detector to which the indicator is to be connected

being brought out of the heated engine compartment so that the connecting leads are not affected by the heat within the compartment. The cell electrolyte has a rather sharply defined melting point. Should the temperature of the beam at any point rise above the melting temperature of the electrolyte heat from the beam will be conducted through the outer tube of the detector to the electrolyte to cause the electrolyte to melt. The electrolyte wets adjacent surfaces of the two dissimilar metallic electrodes and causes an electrical current to be produced which serves to light the indicator lamp 11. Should the temperature of the beam subsequently fall off below the fusion point of the electrolyte, the electrolyte will solidify and current will no longer be produced. The light of the lamp will be extinguished as an indication that the temperature of the beam has been lowered to a safe level.

As various changes may be made in the form, construction and arrangement of the parts herein described without departing from the spirit and scope of the invention and without sacrificing any of the advantages, it is to be understood that all matter herein is to be interpreted as illustrative and not in any limiting sense.

What is claimed is:

1. A fire alarm system comprising an elongated thermal electric cell detector having electrical indicating means in current conducting relationship therewith, said detector comprising an outer electrode of a first metallic element, an inner electrode of a second dissimilar metallic element, nonconductive spacing means disposed therebetween and a fusible salt electrolyte interspersed with said spacer, said electrolyte adapted to melt at a predetermined temperature and to cooperate with the electrodes to produce a current adapted to actuate the indicating means.
2. A fire alarm system comprising an elongated thermal electric cell, and electrical indicating means in current conducting relationship therewith, the thermal electric cell having a tubular electrode formed of a first metallic element, a wire electrode formed of a second dissimilar metallic element, and a glass fiber tape spacer disposed therebetween and contiguous with the two electrodes, said tape being impregnated with a normally solid salt electrolyte, said electrolyte adapted to melt at a predetermined temperature and to cooperate with the electrodes to produce a current adapted to actuate the indicating means.
3. The invention in accordance with claim 2 wherein the tubular outer electrode has been flattened and the inner electrode has the form of an elongated strip.
4. In a fire alarm system of the character described, a tubular outer electrode, a flat inner electrode disposed within said outer electrode, said electrodes being of dissimilar metal, a fibrous spacer element separating said electrodes, and an eutectic mixture of potassium and lithium chlorides and a depolarizer impregnated in said spacer, said mixture adapted to melt at a predetermined temperature to cooperate with said electrodes to develop an electric potential.
5. An overheat system for aircraft engine support members, in which a thermal cell consists in a tubular outer electrode, an inner wire electrode of dissimilar metal, means to space and to depolarize said electrodes, an eutectic salt electrolyte mixture impregnated in said spacer to melt at a predetermined temperature and adapted to cooperate with said electrodes to develop an electric potential, and means to insulate the ends of said electrodes.
6. The system according to claim 5, in which said cell is of indefinite length, is readily flexible, and adaptable to be bent into any type configuration.
7. A system of the character described, in which a thermal cell consists in a tubular outer electrode, a wire inner electrode of dissimilar metal, an inorganic fibrous spacer separating said electrodes to form a sheath of high electrical resistance therebetween, an eutectic mixture of

potassium chlorides, lithium chloride, and a depolarizer impregnated in said spacer, said mixture adapted to melt at a predetermined temperature to cooperate with said electrodes to develop an electrical potential; a glass seal to insulate one end of said cell, and a crimped portion at the opposite end thereof to insulate said electrodes.

8. In a fire alarm system substantially as described, a flexible, thermal detector of continuous length comprising: an outer substantially tubular metallic electrode, an inner concentric electrode being of a second dissimilar metallic element from said outer electrode, a spacer including a flexible fibrous wrapper of continuous length and an eutectic mixture of potassium chloride, lithium chloride and a depolarizer impregnated within said spacer, said spacer being interposed in close fitting relation between said inner and outer electrodes and extending continuously throughout the length thereof, said eutectic mixture adapted to melt at a predetermined temperature

15

level to develop an electrical potential between said electrodes; and an electric indicating means connected in parallel relation with said electrodes, said indicating means being responsive to the development of electrical potential between said electrodes.

9. The invention in accordance with claim 1 wherein said outer electrode constitutes a continuous sheet enclosing said inner electrode, said indicating means being connected across said electrodes at any point.

10. The invention in accordance with claim 8 wherein a plurality of said detectors extend radially and outwardly from said indicating means.
